UNITED STATES PATENT OFFICE

155,351

DESIGN FOR A THERMOSTAT CASING
OR THE LIKE

Emery C. Lee, Elgin, Ill., assignor to Missouri
Automatic Control Corporation, St. Louis, Mo.,
a corporation of Missouri

Application March 29, 1947, Serial No. 138,029

Term of patent 7 years

(Cl. D52—7)

To all whom it may concern:

Be it known that the undersigned, Emery C. Lee, a citizen of the United States, residing in Elgin, Illinois, has invented a new, original, and ornamental Design for a Thermostat Casing or the like, of which the following is a specification, reference being had to the accompanying drawing forming a part thereof, in which:

Fig. 1 is a plan view of a thermostat casing, showing my new design;

Fig. 2 is a front elevation thereof;

Fig. 3 is a bottom view thereof; and

Fig. 4 is a side elevation thereof.

The essential features of the design reside in the portions shown in full lines.

I claim:

The ornamental design for a thermostat casing or the like, substantially as shown and described.

EMERY C. LEE.
